UNITED STATES PATENT OFFICE.

RONALD A. McCANN, OF SWISSVALE, PENNSYLVANIA, ASSIGNOR TO THE UNION SWITCH & SIGNAL COMPANY, OF SWISSVALE, PENNSYLVANIA, A CORPORATION OF PENNSYLVANIA.

RAILWAY-TRAFFIC-CONTROLLING APPARATUS.

Application filed July 19, 1928. Serial No. 293,945.

My invention relates to railway traffic controlling apparatus, and particularly to apparatus of the type wherein train carried governing mechanism is controlled by energy received from the track rails. The present invention relates to the trackway portion of such apparatus, and is particularly applicable to stretches of single track over which traffic moves in both directions.

10 I will describe one form of apparatus embodying my invention, and will then point out the novel features thereof in claims.

The accompanying drawing is a diagrammatic view showing one form of apparatus embodying my invention.

Referring to the drawing, the reference characters 1 and 1^a designate the track rails of a stretch of railway track over which traffic moves in both directions. These rails are divided by insulated joints 2 into blocks or sections, such as A—B, B—C, and C—D. The section B—C is equipped with apparatus embodying my invention, and only enough parts of the apparatus associated with sections A—B and C—D are illustrated to explain the operation of the parts associated with section A—B.

Section B—C is provided with a track circuit comprising a transformer G^b the secondary of which is constantly connected with the track rails adjacent the west end B of the section, and a track relay F^c which is normally connected with the track rails adjacent the east end C of the section. A second track relay F^b is constantly connected with the track rails adjacent the west end of the section, and a second transformer G^c serves at times to supply track circuit current to the section B—C adjacent the west end of the section. The control and operation of these track circuit elements will be explained more in detail hereinafter.

Located adjacent the point B is a signal S^b for governing eastbound traffic through the section B—C, which signal comprises a proceed lamp 3^x, a caution lamp 3^y and a stop lamp 3^z. Located adjacent the point C is a similar signal S^c for governing westbound traffic through the section B—C.

50 Signal S^b is provided with a polarized eastbound home relay H^b, and with an eastbound home repeater relay W^b. Similarly, signal S^c is provided with a westbound home relay H^c and with a westbound home repeater re-

lay W^c. The circuit for the eastbound home relay H^b is from one terminal or the other of the secondary of a transformer 8, through the front or back point of contact 9 of a home relay W^b, front contact 10 of track relay F², back contact 11 of a stick relay E^c, winding of relay H^b and common wire O to the middle point of the secondary of transformer 8. The primary of transformer 8 is constantly supplied with alternating current from a transformer 35, the primary of which is connected with a transmission line L. This transmission line is supplied with alternating current from a source which is not shown in the drawing. It will be noted that relay H^b is controlled by a track relay F² for section C—D and by the home repeater relay W^b for the section to the east of point D, but that relay H^b is not controlled by either of the track relays associated with section B—C. It will, furthermore, be noted that current of one relative polarity or the other is supplied to relay H^b according as home repeater relay W^b is energized or de-energized, the parts being so arranged that when the home repeater relay W^b is energized, relay H^b is energized in the normal direction, whereas, when home repeater relay W^b is de-energized, relay H^b is energized in the reverse direction. In other words, relay H^b is controlled by traffic conditions to the east of section B—C in such manner that this relay is energized in the normal or the reverse direction according as such traffic conditions are safe or unsafe.

The circuit for the westbound home relay H^c is from one terminal or the other of the secondary of a transformer 4, through the front or back point of contact 5 of home repeater relay W^c, contact 6 of the track relay F¹, back contact 7 of an auxiliary relay X^b, winding of relay H^c, and common wire O to the middle point of the secondary of transformer 4. The primary of transformer 4 is supplied with alternating current from a transformer 36 which is constantly connected with the transmission line L. It will be noted that relay H^c is controlled by traffic conditions in the section west of section B—C but not by either of the track relays for section B—C. This relay is energized in normal or reverse direction according as traffic conditions to the west of point A are safe or unsafe.

The circuit for the eastbound home repeater relay W^b is from the secondary of the trans-

former K^c , through contact 12 of track relay F^c , contact 13 of relay H^b in either the normal or reverse position, winding of relay W^b , and common wire O to the secondary of transformer K^c . The primary of transformer K^c is connected with transmission line L . It will be noted that the home repeater relay W^b is energized whenever home relay H^b is energized, provided that track relay F^c is also energized, but that relay W^b is de-energized whenever either relay H^b or F^c or both of these relays are deenergized. Westbound home repeater relay W^c is similarly controlled by contact 14 of track relay F^c and contact 15 of relay H^c in either the normal or the reverse position, so that relay W^c is energized when and only when both relays F^c and H^c are energized.

Associated with the signal S^b is an eastbound stick relay E^b , which is controlled in a manner common to absolute permissive block signaling practice. That is to say, relay E^b has a pick-up circuit including back contact 21 of track relay F^c , back contact 22 of relay F^b and front contact 23 of home repeater relay W^b ; and it has a stick circuit controlled by its own front contact 25 and back contact 24 of track relay F^b . It follows that in accordance with standard practice, relay E^b is normally de-energized, and becomes energized when and only when an eastbound train enters section B—C, whereupon it remains energized as long as such train occupies section B—C. Signal S^c is provided with a westbound stick relay E^c controlled in a similar manner, that is, this relay is provided with a pick-up circuit including back contact 26 of track relay F^c , back contact 27 of track relay F^c and front contact 28 of home repeater relay W^c ; and is provided with a stick circuit including its own front contact 30 and a back contact 29 of relay W^c . It follows that stick relay E^c is normally de-energized and becomes energized when and only when a westbound train enters section B—C, whereupon, it remains energized until such train leaves section A—B.

The eastbound stick relay E^b is provided with an eastbound stick repeater relay P^c , which is located at the point C and is controlled by a front contact 31 of relay E^b through a circuit which is obvious from the drawing. It follows that relay P^c is energized or de-energized according as relay E^b is energized or de-energized.

The primary of track transformer G^b is normally connected with the secondary of line transformer K^b , through back contact 32 of eastbound stick relay E^b , and track relay F^c is normally connected with the rails of section B—C through back contact 33 of the eastbound stick repeater relay P^c . It follows that when a westbound train passes through the section B—C, track circuit cur-

rent is supplied to the rails of this section in advance of the train by transformer G^b . When an eastbound train enters the section, however, relays E^b and P^c become energized, whereupon, the primary circuit for transformer G^b is opened at back contact 32 of relay E^b and track relay F^c is disconnected from the rails by the opening of back contact 33 of relay P^c ; at the same time the primary of track transformer G^c becomes connected with the secondary of line transformer K^c through front contact 34 of relay P^c , so that track circuit current is supplied to the rails in advance of the train by transformer G^c . The reversal of the track circuit for section B—C is in accordance with standard practice, and forms no part of my present invention. The operation of the apparatus for doing this has therefore been very briefly described in the present specification, but a more detailed description of the structure and operation of apparatus for accomplishing track circuit reversal will be found in Letters Patent of the United States No. 1,400,964, issued to me on December 20, 1921, for railway traffic controlling apparatus.

The rails of section B—C are at times supplied with train governing current which flows through the two rails in multiple, and for this purpose a resistance Q^b is connected across the rails at the point B and a second resistance Q^c is connected across the rails at the point C. This train governing current, which is usually termed loop current is furnished by two transformers T^b and T^c located at the western and eastern ends of the section respectively. The primary circuit for transformer T^b is from the secondary of the transformer K^b , through normal contact 16 of relay H^b and the primary of transformer T^b to the secondary of transformer K^b . It follows that the primary of transformer T^b is supplied with current when and only when the eastbound home relay H^b is energized in the normal direction. The secondary circuit for transformer T^b is from the right-hand terminal of this secondary, through the front point of contact 17 of relay E^b , front point of contact 18 of relay P^c to the mid-point of resistance Q^c , then through the two rails 1 and 1^a to resistance Q^b , and from the mid-point of the latter resistance to the left-hand terminal of the secondary of transformer T^b . It follows that this secondary circuit is closed when and only when the eastbound stick relay E^b and the eastbound stick repeater relay P^c are both energized, that is, when and only when an eastbound train occupies section B—C.

The primary circuit for transformer T^c is from the secondary of transformer K^c , through normal contact 20 of westbound home relay H^c , front contact 19 of west-

bound stick relay E^c , and the primary of transformer T^c to the secondary of transformer K^c . It follows that this primary circuit is energized when and only when relay H^c is energized in the normal direction and relay E^c is energized, that is, when and only when a westbound train occupies section B-C and traffic conditions to the west of point A are safe. The secondary circuit 10 for transformer T^c is from the right-hand terminal of this secondary, through the back point of contact 18 of relay P^c , back point of contact 17 of relay E^b to the mid-point of resistance Q^b , then through the rails 1 and 1^a in 15 multiple to resistance Q^c , and from the mid-point of this resistance to the left-hand terminal of the secondary of transformer T^c . It follows that this circuit is closed when and only when the eastbound stick relay E^b 20 and the eastbound stick repeater relay P^c are both de-energized.

Apparatus embodying my invention is intended for use in connection with train carried apparatus which operates to give a proceed indication when the track occupied by 25 the train is supplied with both track circuit current and loop current, and a stop indication when the supply of either of these currents is discontinued.

30 Assuming that a train equipped with such apparatus is moving toward the east, when this train enters section B-C, relays E^b and P^c will both become energized, so that the train will receive track circuit current from 35 transformer G^c , and will receive loop current from transformer T^b if and only if the eastbound home relay H^b is energized in the normal direction. The opening of track relay F^c will de-energize the eastbound home 40 repeater relay W^b , so that signal S^b will assume the stop indication, but relay H^b will remain energized in the normal direction, and so the supply of loop current to the train will not be interrupted at normal contact 16 45 of this relay.

Assuming now that a westbound train enters section B-C, such train will receive track circuit current from transformer G^b and will also receive loop current from transformer T^c if relay H^c is energized in the normal direction. The opening of track relay F^c will cause the westbound home repeater relay W^c to become de-energized, so that signal S^c will assume the stop indication, but 55 relay H^c will remain energized in the normal direction, and so the supply of loop current will not be interrupted at the normal contact 20 of this relay.

Heretofore the usual practice has been to 60 control the home relays H^b and H^c by one of the track relays for section B-C, so that both of the home relays are de-energized when a train occupies section B-C. This practice makes it impossible to control the 65 supply of loop current by the home relays,

because such control would result in interruption of the loop current as soon as a train enters the section. It is desirable, however, to control the loop current by normal contacts of the home relays, and to make this 70 possible I have eliminated the control of the home relays by the track circuit for section B-C, and have included track relay contacts in the circuits for the home repeater relays W^b and W^c , so that both of the latter relays 75 are de-energized while a train occupies section B-C. Each signal S^b and S^c is controlled by its associated home relay H and home repeater relay W , so that these signals 80 operate in the usual and standard manner.

The proceed lamp 3^g of signal S^b is provided with a circuit which passes from the secondary of transformer K^b , through the front point of contact 38 of relay W^b , contact 37 of relay H^b in the normal position, and lamp 3^g to secondary of transformer K^b . It follows that signal S^b indicates proceed when and only when its home relay H^b is energized in the normal direction and its home repeater relay W^b is energized. Lamp 3^y of signal S^b is provided with a similar circuit which includes front point of contact 38 of relay W^b and contact 37 of relay H^b in the reverse position, so that signal S^b indicates 90 caution when and only when relay H^b is energized in the reverse direction, and relay W^b is energized. The stop lamp 3^r for this signal includes back point of contact 38 of relay W^b , so that signal S^b indicates stop whenever the eastbound home repeater relay W^b is de-energized. Signal S^c is controlled in a similar manner by contact 39 of the westbound home relay H^c and contact 40 of the westbound home repeater relay W^c .

Although I have herein shown and described only one form of apparatus embodying my invention, it is understood that various changes and modifications may be made therein within the scope of the appended claims without departing from the spirit and scope of my invention.

Having thus described my invention, what I claim is:

1. In combination, a section of railway track over which traffic moves in both directions, a track circuit for said section including a track relay, a polarized eastbound home relay controlled by traffic to the east of said section but not by the track relay for said section and arranged to be energized in normal or reverse direction according as such traffic conditions are safe or unsafe, a polarized westbound home relay controlled by traffic to the west of said section but not by the track relay for said section and arranged to be energized in normal or reverse direction according as such traffic conditions are safe or unsafe, an eastbound home repeater relay controlled by said eastbound home relay and by said track relay, a westbound home 115

120

125

130

repeater relay controlled by said westbound home relay and by said track relay, an eastbound signal for said section controlled by said eastbound home and home repeater relays, a westbound signal for said section controlled by said westbound home and home repeater relays, a normally de-energized eastbound stick relay for said section, means for energizing said stick relay when an eastbound train enters said section and for keeping it energized until the train leaves the section, an eastbound stick repeater relay located at the east end of the section and controlled by the eastbound stick relay, a normally de-energized westbound stick relay, means for energizing said westbound stick relay when a westbound train enters the section and for keeping it energized until the train leaves the section, means operating when said eastbound stick relay and said eastbound stick repeater relay are energized to supply train governing current to the rails of said section if and only if said eastbound home relay is energized in normal direction, and means operating when said westbound stick relay is energized to supply train governing current to the rails of said section if and only if said westbound home relay is energized in normal direction.

2. In combination, a section of railway track over which traffic moves in both directions, a track circuit for said section including a track relay, a polarized eastbound home relay controlled by traffic to the east of said section but not by the track relay for said section and arranged to be energized in normal or reverse direction according as such traffic conditions are safe or unsafe, a polarized westbound home relay controlled by traffic to the west of said section but not by the track relay for said section and arranged to be energized in normal or reverse direction according as such traffic conditions are safe or unsafe, an eastbound home repeater relay controlled by said eastbound home relay and by said track relay, a westbound home repeater relay controlled by said westbound home relay and by said track relay, an eastbound signal for said section controlled by said eastbound home and home repeater relays, a westbound signal for said section controlled by said westbound home and home repeater relays, a normally de-energized eastbound stick relay for said section, means for energizing said stick relay when an eastbound train enters said section and for keeping it energized until the train leaves the section, an eastbound stick repeater relay located at the east end of the section and controlled by the eastbound stick relay, a normally de-energized westbound stick relay, means for energizing said westbound stick relay when a westbound train enters the section and for keeping it energized until the train leaves the section, an eastbound train governing trans-

former and a westbound train governing transformer, a primary circuit for said eastbound transformer including a source of current and a normal contact of said eastbound home relay, a secondary circuit for said eastbound transformer including a front contact of said eastbound stick relay and a front contact of said eastbound stick repeater relay as well as the rails of said section, a primary circuit for said westbound transformer including a front contact of said westbound stick relay and a normal contact of said westbound home relay as well as a source of current, and a secondary circuit for said westbound transformer including back contacts of said eastbound stick relay and said eastbound stick repeater relays as well as the rails of said section.

3. In combination, a section of railway track over which traffic moves in both directions, a track circuit for said section including a track relay, a polarized eastbound home relay controlled by traffic to the east of said section but not by the track relay for said section and arranged to be energized in normal or reverse direction according as such traffic conditions are safe or unsafe, a polarized westbound home relay controlled by traffic to the west of said section but not by the track relay for said section and arranged to be energized in normal or reverse direction according as such traffic conditions are safe or unsafe, an eastbound home repeater relay controlled by said eastbound home relay and by said track relay, a westbound home repeater relay controlled by said westbound home relay and by said track relay, an eastbound signal for said section controlled by said eastbound home and home repeater relays, a westbound signal for said section controlled by said westbound home and home repeater relays, means operating when an eastbound train passes through said section to supply train governing current to the rails of the section if and only if said eastbound home relay is energized in normal direction, and means operating when a westbound train passes through said section to supply train governing current to the rails of the section if and only if said westbound home relay is energized in normal direction.

4. In combination, a section of railway track over which traffic moves in both directions, a track circuit for said section including a track relay, a polarized eastbound home relay controlled by traffic to the east of said section but not by the track relay for said section and arranged to be energized in normal or reverse direction according as such traffic conditions are safe or unsafe, a polarized westbound home relay controlled by traffic to the west of said section but not by the track relay for said section and arranged to be energized in normal or reverse direction according as such traffic conditions are safe

or unsafe, an eastbound home repeater relay controlled by said eastbound home relay and by said track relay, a westbound home repeater relay controlled by said westbound home relay and by said track relay, an eastbound signal for said section controlled by said eastbound home and home repeater relays, a westbound signal for said section controlled by said westbound home and home repeater relays, means operating when an eastbound train passes through said section to supply train governing current to the rails of the section which current flows through the two

track rails in multiple, said means being effective if and only if said eastbound home relay is energized in normal direction, and means operating when a westbound train passes through said section to supply train governing current to the rails of the section which current flows through the two track rails in multiple, said means being effective if and only if said westbound home relay is energized in normal direction.

In testimony whereof I affix my signature.

RONALD A. McCANN.
